UNITED STATES PATENT OFFICE.

WILLIAM J. GOING, OF AMSTERDAM, NEW YORK, ASSIGNOR TO GENERAL TEXTILE MACHINERY COMPANY, OF YARDLEY, PENNSYLVANIA.

DYEING APPARATUS.

1,295,155.

Specification of Letters Patent. Patented Feb. 25, 1919.

Application filed April 12, 1917. Serial No. 161,400.

To all whom it may concern:

Be it known that I, WILLIAM J. GOING, a citizen of the United States, residing at Amsterdam, in the county of Montgomery 5 and State of New York, have invented certain new and useful Improvements in Dyeing Apparatus, of which the following is a full, clear, and exact description, such as will enable others skilled in the art to which 10 it appertains to make and use the same.

This invention relates to dyeing apparatus, scouring apparatus and the like and with regard to its more specific features, to circulating dyeing machines.

15 One of the objects of this invention is to provide a device of the character described which will satisfactorily perform the necessary operations but which will not require such frequent repairs and constant supervision.

20 Another object of the invention is to provide a device of the character described which will facilitate and expedite the handling of the material.

25 Another object of the invention is to provide a device of the character described which will secure a better and more uniform action of the liquor on the material and more specifically a better and more uniform dyeing and which will effect a better circulation 30 of the liquor.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

Many features of the invention are applicable to a wide variety of uses but inasmuch as certain practical results are attained when they are embodied in a dyeing apparatus, the 45 invention is illustrated as so embodied, and the liquor will be referred to as a dyeing solution, although it will be apparent that when the invention is otherwise embodied the solution may be of a different character.

50 In the accompanying drawings forming part of this specification wherein similar reference characters refer to similar parts throughout the several views:—

Figure 1 is an elevation of an apparatus in

accordance with this invention showing four 55 dyeing tubs.

Fig. 2 is an elevation of one of the dyeing tubs, showing the operating mechanism thereof.

Fig. 3 is a sectional view through the tub 60 showing the circulating devices.

Fig. 4 is a sectional view through the tub at right angles to Fig. 3,

Fig. 5 is a side elevation of one of the tubs showing the relation of the traveling 65 hoisting mechanism thereto.

Figs. 6, 7 and 8 are a front elevation, a side elevation, and a plan view to an enlarged scale of the hoisting mechanism.

Fig. 9 is a detail of the drive for the hoisting apparatus; and

Figs. 10 and 11 are details of the controlling mechanism for the circulating apparatus.

As illustrated there is provided a plurality of dyeing tubs 1 over which will be supported two parallel beams, as 2, which serve as a track for a traveling hoisting apparatus 3. Each of the dyeing tubs 1 will comprise a vat 4 adapted to contain the dyeing solution, and a support or rack 5 for the material to be dyed. Means are preferably provided for maintaining a circulation of the dyeing solution in the vat, illustrated as propellers 6 which will be arranged to maintain a circulation of the dyeing solution through the vat over the material to be dyed. 75 80 85

As shown in Fig. 3, the vat may be divided into separate portions, as by a partition 7 to form a dyeing chamber, as 8, and a return 90 flow chamber, as 9, which chambers are connected at both top and bottom. The propellers 6 are preferably situated in the chambers 9 and a suitable housing 10 and deflectors 11 may be provided to assist the propeller in moving the dyeing solution. By the arrangement described, the rotation of the propeller 6 will cause the circulation of the dyeing solution underneath the partition 7 and up through the dyeing chamber and over the top of the partition 7, back into the chamber 9, or the reverse, dependent upon in which direction the propeller 6 is rotated. 95 100

There is preferably provided a return flow chamber 9 at each end of the vat, each containing a propeller 6 so that each propeller needs to maintain a circulation for but one half of the vat, and the lower portion of the 105

vat may be divided into two portions, one under the influence of each propeller by a separator.

In order to direct the current of the dyeing solution where it flows from the chamber 9 under the partition 7, and up into the chamber 8, directly upwardly, there is provided in the bottom of the vat below the chamber 8 suitable deflectors, as 12. These deflectors are intended to receive the incoming liquid at a small angle to the direction of flow, and gradually to change the direction of flow to vertical as the flow current enters the dyeing chamber with as little eddying as practicable. They are illustrated as practically constructed having an inclined portion 13 to receive the incoming solution and a straight portion 14 to direct the same upwardly. These deflectors 12 will be spaced from the bottom of the vat to form a channel, as 15, to permit the distribution of the incoming current over the area of the bottom of the vat, and those of the deflectors 12 which are nearest to the chamber 9 will be spaced from the bottom further than the others in order that the cross-sectional area of channel 15 may increase in size as the amount of fluid to be carried increases.

In order to further assist in causing the fluid to be uniformly distributed over the area of the vat, those deflectors which are nearer to the chamber 9 will be closer together than those which are further off.

In order to cause the current of the dyeing solution to be deflected there may be provided upon the cover suitable deflectors, as 16, each of which as shown is of a triangular cross-section whereby the bank of deflectors presents a saw tooth construction.

Means are provided for rotating the propellers to cause the circulation of the dyeing fluid and in order to secure uniformity in the dyeing operation, means are provided to reverse the direction of rotation of the propeller to secure a reversal in the direction of the circulation of the dyeing solution.

In the form of reversing operating mechanism shown, there is journaled above each of the vats 2 on a suitable frame 19 which frame may also support the track 2, a shaft 20 which may be connected by any convenient means as by a chain 21 to a drive shaft 22 which may be conveniently journaled on the frame 19 parallel to the beam 2. An auxiliary shaft 23 adapted to be connected by either one of two chains of mechanism to the shaft 20 contains at its outer end a bevel gear 24 meshing with a bevel gear 25 on a vertical shaft 26 which is adapted to drive through the medium of bevel gears 27 and 28 a horizontal shaft 29 which is arranged to drive the propellers 6 through the medium of bevel gear 30 and 31. By this construction the propellers will be rotated in either a forward or reversed direction as

the shaft 23 is rotated either forward or reversed.

Loosely journaled on the shaft 23 are two gears, 32 and 33. The gear 32 meshes directly with the gear 34 keyed to the shaft 20 and the gear 33 meshes with a gear 35 which in turn meshes with a gear 36, also keyed to shaft 20. By this construction the gears 32 and 33 will rotate in reverse directions. Means are provided for connecting the shaft 23 with either the gear 32 or 33 comprising a pair of clutches 37 and 38 connected for alternative operation by a yoke 39, whereby the shaft 23 is rotated in either a forward or reversed direction as the yoke 39 is thrown either to the left or right.

In order to secure the automatic shifting of the yoke 39 there is pivoted to a cross piece 40 on the frame work of the apparatus a two-armed member or lever 41 having a pin 42 arranged to engage the lug 43 on the yoke 39. The lever 41 is provided with two cam surfaces as 44 and 45 in position to be engaged alternately by a tappet or pin 46 adapted to be moved in an endless path, as by being rotated at slow speed. For the purpose of rotating the pin 46 it is mounted on a gear 47 journaled to the frame of the machine, meshing with a worm 48 on a worm shaft 49 also journaled on the frame; the shaft 49 is operated by a suitable train of gears from the shaft 20 which train of gearing preferably includes a change speed device.

As illustrated, there is keyed to the shaft 20 a pinion 50 meshing with a gear 50' which may be loosely journaled on the shaft 23, and fastened to the gear 50' is another gear 51 of different diameter. Splined to the one shaft 49 is a member 52 having two gears as 53 and 54 adapted to mesh respectively with the gears 50' and 51. The gears 53 and 54 are spaced a different distance apart from the gears 50' and 51, and the member 52 is adapted to slide on the shaft 49 whereby the gear 54 may be brought into mesh with the gear 51 or the gear 53 may be brought into mesh with the gear 50' as desired, whereby the shaft 49 may be driven from the shaft 20 at two different speeds, at will. A suitable lever 55 may be pivoted to the frame work to permit the ready shifting of the member 52.

By the construction outlined, the rotation of the shaft 20 will cause the rotation of the pin 46 about the journal of the gear 47 to engage alternately the cam 44 and the cam 45 whereby the clutches 37 and 38 are brought into engagement alternately, thus reversing the direction of rotation of the propellers twice for each revolution of the pin 46 about the axis of the gear 47. In order to enable the pin 46 to be moved to a position where it will not engage the cam 44 and 45, the pin 46 may be mounted on the

end of a lever as 56 which may be pivoted eccentrically upon the gear 47 whereby it may be swung into either of the two positions 57 or 58, in the first of which it is 5 sufficiently eccentric from the journal of the gear 47 to coöperate with the cams 44 and 45, and in the second of which it will not coöperate with the cam. A suitable bracing member as 60 may be provided having openings at 57 and 58 into which the pin 46 may be thrust to hold the arm 56 in either of its adjusted positions.

In order to retain the lever 41 in either of its extreme positions or in a central position, 15 there may be provided a lever 61 pivoted to the frame work, having three notches as 62, 63 and 64, and there may be provided on the lever 41 a pin 65 to coöperate with the notches. A spring 66 may be provided to 20 thrust the lever 61 upwardly to cause the notches 62, 63 or 64 to engage the pin 65. Means may be provided if desired for disconnecting the shaft 20 from the shaft 22 comprising a clutch 70 operated by a lever 25 71 controlled by a rod 72.

The support or rack 5 for the material to be dyed comprises two side members 75, held in spaced parallel relation by cross member 76. The members 75 may be 30 notched as at 77 to receive the ends of cross rods 78 upon which the material to be dyed may be placed, and the notches 77 will be so spaced as to afford proper spacing of the material upon the different rods. The rack 35 5 is conveniently supported from the cover 79 of the vat 1 by means of rods 80 extending downwardly from the cover through the rack and locking pins 81 adapted to pass through openings 82 in the end of the rod 80 40 below the rack 5, to support the same. Suitable chains as 82^a may be provided to prevent the pins 81 being lost.

The traveling hoisting mechanism 3 for lifting the covers of the vats carrying with 45 them the racks 5 and the material to be dyed, and for transporting them as desired, comprises a frame 83 having wheels 84 adapted to run upon the roadway 2. Journalized upon the frame 83 is a shaft 85, 50 having at each end a sheave 86 on which is adapted to be wound a flexible supporting element as a chain 87 having at its outer end a hook 89 adapted to coöperate with eyes 90 upon the cover 79 of the dyeing vat. Also 55 keyed to the shaft 85 is a sheave 91 which is preferably of smaller diameter than the sheave 86 in order to cause considerable motion of the chain 87 for a small rotation of the shaft 85. A chain 92 is adapted to be 60 wound and unwound from the sheave 91 and is attached at the other end to pin 93 eccentrically fastened upon a gear 94 journalized on the frame 83. Suitable rotary guides 95 are provided to secure proper running of the chain on sheave 91 in spite of

changes in the angularity in the pull of the pin 93 on the chain. Journalized also on the frame 83 is a worm shaft having a worm 96 for engagement with the teeth of the gear 94 for rotating the same. A shaft 97 journalized on the frame 83 carries at its outer end a sprocket 98 which is driven by a power transmitting member as a traveling driving chain 99. Journalized for rotation upon the shaft 97 is a gear 100 meshing with gear 101 70 upon the worm gear shaft 96, and splined to the shaft 97 is a member 102 of a friction clutch adapted to coöperate with a mating member 103 connected to the gear 100 for driving the gear 100 from the shaft 97. A 80 suitable handle 104 may be provided to shift the member 102 into and out of engagement with the member 103 connecting and disconnecting the hoisting mechanism from the drive. 85

For the purpose of causing the traveling hoist to move along the track, one of the pairs of wheels 84 may be fast upon their shaft 109, and there may be splined to this shaft a member 110 adapted to be moved 90 to the right or left by a suitable handle 111. Loosely journalized upon the shaft 109 are two members 112 and 113, one of which 112 may be driven by a chain 114 on a sleeve 117 loosely journalized upon the shaft 85 and the 95 other member 113 may be driven from the sleeve 117 through the medium of gears 118 and 119. The sleeve 117 may be driven by a chain from the shaft 97. By this construction the members 112 and 113 will be driven 100 in opposite directions, and the wheels 84 may be moved forward by bringing the member 110 into engagement with the members 112 or 113.

The driving chain 99 may be carried on 105 suitable sprockets 125 and 126 on the frame 19, at opposite ends of the track 2. The upper reach of the chain may be supported by suitable sprockets 127, and the lower reach of the chain may be allowed to run 110 in a runway 128. The sprocket 98 is in engagement with the lower reach of the chain. In order to pick up the chain 99 out of the runway 128, and carry it over the sprocket 98 and keep it in mesh therewith, guiding 115 sheaves, as 129, may be provided.

A suitable source of power, as an electric motor 130 may be mounted on the frame work for driving the driving shaft 22, and the driving chain 99, and suitable speed reducing connections may be introduced between the motor and the shaft 22 and chain 99 to cause them to be driven at the proper speeds.

As illustrated the motor 130 is connected 125 to the shaft 22 through a speed reducing gearing 131 and a chain 132 running over sprockets 133 and 134, the former being on a shaft connected to one of the train of gears 131 and the latter on the drive shaft 22. 130

The motor 130 is connected to the chain 99 by the shaft 135 which may be connected to the motor shaft 136 by bevel gearing and to the shaft 137 on which the sprocket 125 is rigid by a chain 138, passing over a sprocket 139 on the shaft 137 and a sprocket 140 on the shaft 135. By properly proportioning the train of gearing 131, and relative sizes of the sprocket wheels 133 and 134, 10 and 139 and 140, the speed of the shaft 22 and the driving chain 99 may be regulated.

In order to permit the driving of the propellers 6 without the necessity of using stuffing boxes, all that portion of the driving mechanism below the level of the dyeing solution, including the shaft 29 and the gears 31, 27 and 28, is kept submerged in the dyeing solution and to this end is inclosed in a water-tight housing comprising, 15 as shown, a horizontal tubular portion 150 surrounding the shaft 29, a vertical tubular portion 151 surrounding the shaft 26, a chambered portion 152 surrounding the gears 30 and 31 at one end of the shaft 29 20 and a second chambered portion 153 for inclosing the gears 27, 28 and 31 at the other end of the shaft 29. The chambered portions 152 and 153 are connected by water tight joints with the side of the vat and with 25 the tubular portions 150 and 151. By this construction, the dyeing solution may be allowed to fill the housing for the driving mechanism without danger of leakage of the dyeing solution out of the vat.

30 The operation of this device is as follows:

The rack 5 for one of the vats may be supported on suitable supports outside the vats, underneath the track 2 in which position the rods 78 each carrying its quantity 40 of the material to be dyed may be placed in the notches 77 of the side member 75. A cover 79 supported by the traveling hoisting mechanism 3 through the medium of the chains 87 may now be lowered over the rack 5 until the rods 80 pass through the rack and the locking pins 82 are put in place to enable the cover to support the rack. The rack 5 carrying with it the material to be 45 dyed may now be lifted with the cover 79 by shifting the handle 104 to cause the members 102 and 103 to engage. When the rack and cover have been lifted sufficiently to allow them to be carried over the dyeing 50 vat, the handle 104 may be shifted back to cause the disengagement of the members 102 and 103.

Thereupon by shifting the handle 111 to cause the member 110 to come in contact with 60 the proper one of the members 112 or 113, the traveling series will be caused to move upon the track 2 to carry the cover and frame to a position over the desired dyeing vat, whereupon its motion may be stopped 65 by shifting the lever 111 back to its former

position. The material to be dyed together with the rack and the cover may then be lowered into the dyeing vat by shifting the handle 104.

A shifting of the operating rod 72 causing the engagement of the groove 70 will now start the propellers 6 revolving through the medium of the operating mechanism, provided that the lever 41 is in either of its extreme positions, right or left. The propeller 6 will rotate in alternate directions, changing directions twice for each revolution of the gear 47. The length of time that the propeller 6 will rotate in one direction before reversing may be changed by shifting 75 the gear 55 to cause the shaft 49 to rotate the gear 47 at higher speed.

Should it be desired to cause the reversal of the direction of the propellers 6 by hand instead of automatically, the pin 46 may be 80 removed from the opening 57 inserted in the hole 58 whereupon the rotation of the gear 47 will have no effect upon the position of the lever 41. The direction of the propeller 6 may then be changed by shifting the member 90 41 to right or left at will.

The rotation of the propellers 6 will cause the circulation of the dyeing fluid through the chamber 9 into the tanks 8 and the shape of the baffle 12 having a vertical portion 14 95 will cause the dyeing solution to enter the chamber 8, at the time when its flow is upwardly toward the chamber 8, to be vertical and the form of the deflector 16 is such as to cause the deflection of the current and 100 dyeing solution onto the top of the material to be dyed. When the direction or flow is reversed the deflector 16 will perform the same functions as before and the deflectors 14 will insure that the dyeing solution leaves 105 the chamber 8 directly downwardly.

Thus by the above construction are accomplished, among others, the objects hereinbefore set forth.

As many changes could be made in the 110 above construction and many apparently widely different embodiments of this invention could be made without departing from the scope thereof, it is intended that all matter contained in the above description or 115 shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a dyeing machine or the like, in combination, a vat, means for causing a cir- 120 125

culation of the liquor in the vat, means for automatically reversing the circulation of the liquor at predetermined intervals and means for changing the interval between reversals.

2. In a dyeing machine or the like, in combination a vat, means comprising power driven propellers, for causing a circulation of liquor in the vat, and means for automatically reversing the direction of circulation of the liquor at predetermined intervals comprising two members rotating in opposite directions and a member adapted to be brought into operative engagement with either one of said oppositely rotating members and means for connecting the last mentioned member to said propellers.

3. In a dyeing machine or the like, in combination, a vat, propellers for causing the circulation of the liquor in the vat, means for driving the propellers and for alternately reversing the direction of motion thereof at predetermined intervals comprising two members rotating in opposite directions, a third member operatively connected to said propeller, adapted to be connected to the one or the other of said oppositely rotating members, a lever having a cam surface thereon, connected to said third member, and a constantly rotating element having means for engaging the cam to operate the lever to move the third member into operative connection with one of the oppositely rotating members and means for causing the reversal of the lever to cause the connection of said third member with the other of said oppositely rotating members and means for operating said constantly rotating member.

4. In a dyeing machine or the like, in combination, a vat, means for causing a circulation of the liquor in the vat, and means situated above the stream of circulating liquid for directing the circulating liquor downwardly on top of the material in the vat.

5. In a dyeing machine or the like, in combination, a vat, means for causing a circulation of liquor in the vat, and means comprising a series of angular deflectors supported above the stream of circulating liquor in the vat for directing the circulating liquor downwardly on top of the material.

6. In a dyeing machine or the like, in combination, a vat having a cover, means for causing a circulation of liquor in the vat, and means, comprising a series of triangular deflectors attached to the cover of the vat, for directing the circulating fluid downwardly on top of the material to be treated.

7. In a dyeing machine or the like, in combination, a vat, means for causing a circulation of liquor in the vat, and means for directing the flow of the current vertically in the vat, comprising baffles having an in-

clined edge, farthest from the dyeing chamber and a substantially vertical edge toward the dyeing chamber whereby the liquor is gradually brought to assume a direction substantially vertical.

8. In a dyeing machine or the like, in combination, a vat, means for causing a circulation of liquor in the vat, means external to the vat for operating the circulating means and a liquid tight casing communicating with the interior of the vat inclosing said operating means.

9. In a dyeing machine or the like, in combination, a vat having a dyeing chamber therein, means for maintaining a circulation of liquor in the dyeing chamber between the top and bottom thereof and horizontally above and beneath the dyeing chamber in the vat, and horizontally spaced baffles situated in the horizontal current at the upper part of the dyeing vat presenting an inclined surface for deflecting the circulating fluid to change its direction between the horizontal and the vertical currents.

10. In a dyeing machine or the like, in combination, a vat having a dyeing chamber therein, means for maintaining a circulation of liquor in the dyeing chamber between the top and bottom thereof and horizontally above and beneath the dyeing chamber in the vat, and horizontally spaced baffles situated in the horizontal current at the upper part of the dyeing vat comprising triangularly shaped members with the apex of the triangle downwardly so as to present an inclined surface for deflecting the circulating fluid to change its direction between the horizontal and the vertical currents.

11. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch elements and either of the other two comprising a power driven tappet movable in an endless path and a member adapted to be moved by said tappet to effect said engagement.

12. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected

- to said propelling mechanism, and means adapted to effect engagement between said third clutch element and either of the other two comprising a power driven tappet movable in an endless path and a member adapted to be moved by said tappet to effect said engagement, said tappet being adjustable into and out of position to move said member.
- 10 13. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and hand-operated means adapted to change the speed of movement of said tappet.
- 15 14. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.
- 20 15. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.
- 25 16. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.
- 30 17. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.
- 35 18. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.
- 40 19. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.
- 45 20. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and means adapted to retain said member in the position to which it is moved by said tappet.

by said tappet in either of opposite directions.

15. In a dyeing machine or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power driven tappet movable in an endless path, a member adapted to be moved by said tappet to effect said engagement, and hand-operated means adapted to change the speed of movement of said tappet.

16. In a dyeing machine, or the like, in combination, a vat, propelling mechanism for causing circulation of the liquor in the vat, and means for driving the propelling mechanism and automatically reversing the direction of motion thereof comprising a pair of clutch elements, means adapted to drive said elements in opposite directions, a third clutch element operatively connected to said propelling mechanism, and means adapted to effect engagement between said third clutch element and either of the other two comprising a power-driven tappet movable in an endless path, a two-armed lever between the arms of which said tappet moves and with each of which the tappet is adapted to coöperate, said lever being connected to effect said engagement on movement in one direction or the other from an intermediate position.

In testimony whereof I affix my signature, in the presence of two witnesses.

WILLIAM J. GOING.
